MOUNTING MEANS FOR SIDE DELIVERY BOARD FOR MOWING MACHINE

Friedrich Philipp, Remscheid-Lennep, Germany, assignor to Gebrüder Busatis, Remscheid-Lennep, Germany, a corporation of Germany

Application November 9, 1953, Serial No. 391,009

Claims priority, application Germany November 12, 1952

3 Claims. (Cl. 56—314)

The present invention relates to a connection of a side delivery board with the outside-shoe of mowing machines.

The side delivery board, which is supported by the outside-shoe of the mowing beam, forms a street in the harvested cut goods, in which street the wheels of the vehicle carrying the mowing machine may run without running over the harvested goods.

It is one object of the present invention to provide a connection between the side delivery board and the outside-shoe of the mowing machine, which may be released without the use of any tools and also be easily reinstated into its connected position.

It is of greatest importance to provide the possibility for easy removal of the side delivery board and for easy connection of the same in connection with mowing machines associated with a tractor where the side delivery board must be removed quite often, since the tractor is used for other labor between the mowing periods, the bulky side delivery board being troublesome when not in use.

Some fast operating connections are already known for the side delivery board with the outside-shoe of a mowing machine which connections are, however, not very suitable for the practical mowing work, since these known connections include loose parts as for instance screws upon removal of the side delivery board, which parts are subject to loss and in addition also require a change in the structure of the outside-shoes.

It is, therefore, another object of the present invention to provide a connection of the side delivery board with the outside-shoe of the mowing machine which avoids the inherent drawbacks of the known connections.

It is still another object of the present invention to provide a connection of the side delivery board with the outside-shoe of a mowing machine in which the side delivery board is secured to the outside-shoe of the mowing beam by means of a resiliently mounted latch secured to the latter, the side delivery board being rotatable upon the said latch in order to meet the unevenness of the soil, while prevented from further movement beyond the said limited rotating movement by inter-engagement between the side delivery board and the outside-shoe, the side delivery board having a notch with a slot open to the outside, and the latch of the outside-shoe springing into the notch of the side delivery board, thereby introducing a bolt of the outside-shoe, on which the resiliently mounted latch slides into the notch of the side delivery board, the necessary clamping of the securing head of the side delivery board between the outside shoe and its latch being eased by a wedge-shaped formation of the portion of the side delivery board carrying the notch slot.

The construction in accordance with the present invention permits the connection and disconnection, respectively, of the side delivery board with the outside-shoe in one single manual step, since it is merely necessary to provide a forced turning of the side delivery board upon the finger of the outside-shoe until the notch of the side

2

delivery board disengages itself and thereby releases the latter and in order to connect the side delivery board again merely the opposite single manual step is necessary. The resistance encountered in the disengagement of the notch is adjustable by proper change of the spring force of the latch.

It is to be understood that the same result may be achieved by reversing the provision of the latch and notch on the side delivery board and the outside-shoe, respectively.

With these and other objects in view, which will become apparent in the following detailed description, the present invention will be clearly understood in connection with the accompanying drawings, in which:

Figure 1 is a side elevation of a securing head of a side delivery board secured to the end of an outside-shoe;

Fig. 2 is a section along the lines 2—2 of Fig. 1;

Fig. 3 is a section along the lines 3—3 of Fig. 1;

Fig. 4 is an axial section through the end portion of the outside-shoe, similar to the showing in Fig. 2; and

Fig. 5 is an axial section through the side delivery board similar to the showing in Fig. 2.

Referring now to the drawing, the outside-shoe 1 of a mowing machine has a bolt 2 which serves as a guide

for the calotte-shaped latch 3 which is forced into position by a helical spring 4. The latch 3 rests in a notch 5 of complementary shape disposed in the securing head 6 of the side delivery board 7, as clearly shown in Figs.

1—3. In this manner the side delivery board is connected for relative rotatable movement with the outside-shoe 1. In order to bring about this connection and disconnection, respectively, with the above described construction, the notch 5 of the securing head of the side delivery board is open to the outside by means of the slot 8. The bolt 2 may be inserted into the notch 5 through the slot 8, whereupon the latch 3 springs into the notch 5. Since it is necessary to press manually the securing head of the side delivery board between the side wall of the outside-shoe and the latch 3, which is under pressure of the spring 4, in order to simplify this connecting step the portion of the securing head 6 of the side delivery board which carries the slot 8 is of wedge shape, as clearly shown in Fig. 3.

The outside-shoe 1 and the securing head 6 of the side delivery board are additionally connected by means of the finger 9 of the former, the said finger 9 engaging a slot 10 of the securing head with sufficient play to permit the side delivery board to follow the unevenness of the soil.

While the side delivery board 7 is shown in Fig. 2 on one side of the securing head 6, the side delivery board 7 may be disposed at the opposite side of the securing head 6, as disclosed in Fig. 5, without changing the function of the device, the choice of the side being dependent upon the material used.

In order to bring about connection and disconnection, respectively, of the side delivery board, it is merely necessary to turn the latter upon the finger 9 of the outside-shoe, whereupon the latch 3 of the outside-shoe becomes engaged and disengaged, respectively, with the notch 5 of the securing head of the side delivery board.

The notch connection and the turning connection of the side delivery board with the outside-shoe may be varied and such variations are to be considered within the scope of the present invention, as long as the same function and the same effect is achieved.

While I have disclosed one embodiment of the present invention, it is to be understood that this embodiment is given by example only and not in a limited sense, the scope of the present invention being determined by the objects and the claims.

I claim:

1. An easily releasable connection of the side delivery board with the outside-shoe of the mowing beam of a mowing machine comprising a latch resiliently mounted on the said outside-shoe, and the said side delivery board having a notch receiving the said latch and securing the said side delivery board to the said outside-shoe for relative rotation, means for interengaging the said outside-shoe with the said side delivery board to limit the relative rotating movement to slight movements in order to follow the unevenness of the soil, and the said notch of the said delivery board extending into a slot leading to the outside, and a bolt extending from the said outside-shoe, and the said latch being slidingly mounted on the said bolt, so that the said bolt may enter the slot and bring the said resiliently mounted latch into the said notch of the said delivery board.
2. The connection, as set forth in claim 1, in which the portion of the said side delivery board containing the said slot leading to the said notch is of wedge shape, in order to ease the insertion of the said side delivery

10 board between the said outside-shoe and the said latch secured thereto.

15 3. The connection, as set forth in claim 1, in which the said means for interengaging the said outside-shoe with the said side delivery board comprises a finger extending from the said outside-shoe and the said side delivery board has a slot disposed adjacent the said notch, the said last mentioned slot receiving the said finger of the outside-shoe, the said finger being slightly movable in the said slot, so that the said side delivery board is permitted to follow the unevenness of the soil by limited rotating movement upon the said bolt as pivotal axis.
